UNITED STATES PATENT OFFICE.

WILLIAM H. DE WICK, OF BROOKLYN, NEW YORK.

MANDOLIN.

1,018,651.

Specification of Letters Patent. Patented Feb. 27, 1912.

Application filed May 16, 1910. Serial No. 561,562.

To all whom it may concern:

Be it known that I, WILLIAM H. DE WICK, a citizen of the United States, residing in the borough of Brooklyn, county of 5 Kings, State of New York, have invented a certain new and useful Improvement in Mandolins, of which the following is a specification.

The object I have in view is to produce 10 an instrument of the mandolin type, that is, one having a wooden head or deck, in which the head or deck will be rigidly held in place, whereby the "treble strings" will be caused to give a loud and brilliant tone, and 15 the head or deck will be prevented from sagging.

A further object is to produce an instrument in which the sound openings will be concealed.

20 A further object is to produce an instrument in which all strains will be removed from the head or deck and in which no part of the instrument will be in contact with the head or deck except the bridge.

25 These and further objects will be pointed out in the following specification and claims, taken together or separately.

In the accompanying drawings Figure 1 is a plan view of a musical instrument embodying my invention; Fig. 2 is a section on the line *a—a* of Fig. 1; Fig. 3 is a section on the line *b—b* of Fig. 2; Fig. 4 is a similar view showing another modification, and Fig. 5 is a side view of a modified form of 35 brace.

1 indicates the back of the instrument to which is rigidly secured a barrier 2 which is preferably cylindrical in form and of considerable thickness. Secured to the back 40 1 and preferably arranged concentrically with reference to the barrier 2 is a hoop 3 and to the top of the hoop is secured, by gluing or otherwise, a head or deck 4 which, in the preferred embodiment of my invention, is flat and imperforate. Between the barrier 2 and hoop 3 I provide an annular space 5 and in the hoop 3 is a plurality of 45 sound openings 6—6. Rigidly secured to the back, hoop, and deck, is a plurality of 50 rectangular, open braces 7 each provided at the center of its top and bottom members with an enlargement 8 to give added stiffness. The enlargement 8 may be omitted if desired. The ends of the braces are pro-

vided with feet 9 which project through 55 the openings 6 and are secured to the barrier 2. Spacing blocks 10 and 11 are secured in place between the barrier and hoop at diametrically opposite points. The block 10 is for the purpose of adding 60 strength at the point where the neck 12 is secured to the body. The neck 12 is provided with a dowel 13 which projects through the barrier and enters a recess 14 in the block 10, and the finger board 15 is 65 secured to the neck in the usual manner and projects over the deck 4 but does not come in contact therewith. The block 11 is diametrically opposite the block 10 and gives an additional support for the usual tail- 70 piece 16 which may be secured in place by screws or otherwise. Strings 17 are secured to the tail-piece in the ordinary manner, and to the usual pegs or keys at the outer end of the neck, and a bridge 18 is placed on 75 the deck at the proper place and supports the strings at that point. The braces 7 give added stiffness to the deck and prevent sagging thereof.

In all wooden deck instruments, as far as 80 I am aware, the decks are caused to sag by reason of the strains put upon them by the strings and because of insufficient bracing. By placing the sound openings in the hoop as shown the deck is left imperforate, there- 85 by adding to its stiffness and by means of the barrier the sound openings are concealed from view, thus adding to the appearance of the instrument.

In the modification shown in Fig. 4 the 90 barrier and the sound openings in the hoop are omitted, the sound opening being placed in the deck, and the neck and the tail-piece are secured to the hoop 3.

In Fig. 5 I have shown the blocks 10' and 95 11' secured to the barrier 2 only, thus leaving the hoop 3 free at all points, and the barrier is shown as having the same height as the body only where the blocks 10' and 11' are placed, and tapers to nothing midway between those points.

It is obvious that the sound openings in the hoop may be of any size or shape and the number and position may be varied as desired.

105 It is obvious that various modifications may be made without departing from the spirit or scope of my invention.

Having now described my invention what I claim and desire to secure by Letters Patent is as follows:

1. A musical instrument of the class described, comprising a deck, a hoop supporting the deck, and a back secured to the hoop, said back extending beyond the hoop and carrying a barrier separated from the hoop.
2. A musical instrument of the class described, comprising a deck, a hoop supporting the deck, a sound opening in the hoop, a back carried by the hoop, and a barrier supported on the back and concealing the sound opening.
3. A musical instrument of the class described comprising a deck, a hoop supporting the same, sound openings in the hoop, a back carried by the hoop, a barrier supported on the back and separated from the hoop, and a brace by means of which the deck, the back, the hoop and the barrier are secured together.
4. A musical instrument of the class described comprising a flat, imperforate deck, a hoop carrying the same, a plurality of openings in the hoop, a back, a barrier carried by the back and separated from the

hoop and concealing the openings, and a brace secured to the deck, the hoop, the back, and the barrier.

5. In a musical instrument of the class described the combination with a deck, a hoop supporting the same, openings in the hoop, a back carried by the hoop, a barrier secured to the back and a neck and finger board carried by the barrier, of a brace joining the deck, the hoop, and the back, said brace being provided with feet which extend through the openings in the hoop and are secured to the barrier.

6. In a musical instrument of the class described the combination with a deck, a hoop carrying the same, a back carried by the hoop and a barrier carried by the back of blocks carried by the barrier, a neck secured in one of said blocks, and a brace securing together the deck, the hoop, the back and the barrier.

This specification signed and witnessed this 14th day of May, 1910.

WILLIAM H. DE WICK.
